TRIPLE VALVE LAPPING TOOL

James R. Ricketts, Richmond, Calif., assignor to
National Air Brake Service, Inc.Original application December 5, 1927, Serial No.
237,959. Divided and this application October
1, 1929, Serial No. 396,484. Renewed January
17, 1934

4 Claims. (Cl. 51—57)

This application is a division of my copending application entitled "Triple valve lapping machine", filed December 5, 1927, and bearing Serial Number 237,959, now Patent No. 1,749,890, dated March 11, 1930.

This invention relates to machines for lapping the slide valve seats in triple valves.

It is the principal object of the present invention to provide a generally improved lapping tool capable of use in expeditiously and accurately lapping slide valve seats in triple valves.

In carrying out this invention into practice I provide a lapping tool which includes a loosely held disk. This disk is formed with a recess 10 extending coaxially therein to a point short of its grinding surface. This recess is engaged by a pin which bears at the bottom of the recess and at the exact center thereof so that applying pressure to the pin, the proper amount of 20 pressure may be brought to bear on the tool during the operation thereof. I intend that the diameter of the disk be slightly less than the distance between the sides of the slide valve seat so that the tool may be revolved in opposite directions by bearing against opposite sides 25 of the seat on opposite strokes.

One form which the invention may assume is exemplified in the following description and illustrated by way of example in the accompanying drawing, in which:

Fig. 1 is a side elevation of a machine embodying the preferred form of my invention with parts in section to more clearly disclose certain details of construction.

Fig. 2 is an enlarged view of the lapping tool partially in section.

Fig. 3 is a perspective view of the lapping tool showing the same in vertical section.

Fig. 4 is a bottom plan view of the lapping tool.

Fig. 5 is a diagrammatic view showing the slide valve seat of a triple valve in plan with the lapping tool passing thereover and in engagement with one side thereof.

Fig. 6 is a plan view of the machine with parts thereof broken away to more clearly disclose the arrangement of parts.

Referring more particularly to the accompanying drawing, 10 indicates a frame adapted to be bolted to a base structure or bench. This frame is formed with a suitable bearing 11 within which a shaft 12 is journalled. A crank disk 14 is suitably secured on one end of the shaft. To drive the shaft and crank disk the other end of the shaft 12 is fitted with a

loose pulley 15 and a tight pulley 16. These pulleys may be connected by a belt 17 to a suitable driving motor, not illustrated.

The crank disk 14 is provided with an eccentrically positioned wrist pin 23 as disclosed in the drawing, which wrist pin extends outwardly from the crank disk 14 and is connected to one end of a connecting rod 24. The wrist pin 23 is adjustable relative to the center of rotation of the crank disk 14 so that the stroke of the connecting rod 24 may be varied to suit triple valves of different dimensions. This is particularly desirable as it is intended that the stroke of the connecting rod 24 equal the length of the slide valve seat in a triple valve. As these triple valves vary in dimensions it is essential that the stroke of the connecting rod 24 be optional so that the machine may operate efficiently on valves of different sizes.

The frame 10 includes a lower arm 25 which extends longitudinally of the machine in parallelism with the connecting rod 24. At its forward end this arm 25 slidably receives a socket 26 of a table 27. This table is disposed horizontally and its surface is machined to receive a triple valve and to hold the same with its axial center in parallelism with the plane of the disk 14. To secure the triple valve to the table, the latter is formed with bolt holes in alignment with the tapped openings in the bottom flange of the valve, so that the latter may be secured to the table by bolts. The bottom flange of the valve is also provided with a dowel, which may engage a recess formed in the surface of the table so as to properly align the valve with respect to the crank disk 14.

It will be noticed that the socket 26 of the table 27 is provided at its bottom with a clamping screw 28 engageable with the arm 25. By loosening this screw 28, the table and the valve may be adjusted along the arm 25 and that by tightening the screw 28 the table may be rigidly clamped to the arm 25 in proper position relative to the crank disk 14.

In parallelism with the lower arm 25, I provide an upper arm 29 arranged a spaced distance above the lower arm 25 and terminating short of the end thereof. This upper arm 29 slidably receives a crosshead 30 upon which a bell crank lever 31 is pivoted. One of the arms of this lever 31 extends transversely of the machine and is connected at its outer end to the forward end of the connecting rod 24. The other arm of the bell crank lever 31 extends

longitudinally and forwardly of the machine and is rigidly connected to the rearmost end of a flexible lap carrying arm 33.

The forward end of the arm 33 carries a lapping tool 34 with which this application is particularly concerned. The machine just disclosed is fully described and claimed in my copending application above mentioned.

10 The lapping tool 34 is disk-like and is formed with a peripheral groove intermediate its top and bottom surfaces. A retainer member 34a is secured to the arm 33 and is fitted with downwardly and inwardly bent ends which engage the peripheral groove so as to loosely connect the

15 lapping tool 34 to the arm 33.

The lapping tool 34 is formed with a central recess 34c which extends coaxially of the tool from the upper surface thereof to a point closely adjacent its lower or grinding surface. This 20 recess terminates in a point as illustrated in Fig. 2. To engage this recess, the arm 33 is fitted with a bearing pin 34b, the lower end of which is turned to a point. This bearing pin 34b projects downwardly within the recess 34c and its pointed lower end bears at the pointed lower end of the recess 34c. Thus, when pressure is exerted on the arm 33 or the pin 34b, the bearing pin 34b will bear on the lap exactly 25 at the center and adjacent its lower or grinding surface. This causes the entire lapping area of the lapping tool to bear on the surface being lapped with equal pressure.

As shown in Figs. 3 and 4 the working surface 30 of the lapping tool is formed separately from the lapping tool proper. This working surface is cupped and is pressed on the lower end of the lapping tool. After being pressed into place, four radial slots are cut in the working or wearing surface. These slots are for the purpose of 35 retaining the grinding compound utilized and to distribute it equally over the surface being lapped.

When the lapping tool is in use on a machine 40 here disclosed, pressure is brought to bear on the arm 33 by means of a cam 35 and a cam roller 36.

In operation of the lapping tool here disclosed, the machine is placed in operation to reciprocate the arm 33. As the connecting rod 24 moves 45 forwardly toward the triple valve due to the provision of the crank lever 31 the lapping tool 34 will roll against one side of the slide valve seat and at the forward end of the stroke the latter will be moved laterally into engagement with 50 the opposite side of the slide valve seat and roll against this side on the return stroke. Thus, due to the provision of the bell crank lever 31 the lateral position of the lap in the slide valve seat is changed at the end of each stroke and the 55

60

65

70

75

lapping tool is revolved in opposite directions on opposite strokes.

It should be stated that the lapping tool 34 is slightly less in diameter than the dimension between the side walls of the slide valve seat but is greater in diameter than the width of the seat itself. This is clearly illustrated in Fig. 5 of the drawing where 50 represents the side walls of the slide valve seat and 51 represents the sides of the valve seat proper.

80 From the foregoing it is obvious that I have provided an improved lapping tool capable of use in expeditiously and accurately lapping slide valve seats in triple valves.

85 90 While I have shown the preferred form of my invention, it is to be understood that various changes may be made in its construction by those skilled in the art without departing from the spirit of the invention as defined in the appended claims.

95 Having thus described my invention, what I claim and desire to secure by Letters Patent is:

100 1. A lapping tool for lapping the slide valve seat in a triple valve, said tool comprising an arm, a disk having a peripheral groove intermediate its surfaces, a retaining member fixed to the arm and engaging said groove but permitting an amount of relative movement between the disk and the arm, said disk having a recess 105 formed coaxially thereof and extending inwardly just short of its grinding surface, and a bearing member carried by the arm and projecting within said recess to bear against the bottom of the recess at the center of the disk when pressure is placed on the arm.

110 2. A lapping tool of the character described comprising an arm, a disk, means loosely connecting the disk to the arm, and a bearing member carried by the arm and engageable with the disk, said means and said bearing member 115 cooperating to prevent removal of the disk from the arm.

120 3. A lapping tool of the character described comprising an arm, a disk having a peripheral groove formed in its edge intermediate its top and bottom surfaces, and a retaining member carried by the arm and extending into said groove and retaining the disk against removal from the arm but permitting relative movement 125 between the disk and the arm.

130 4. A lapping tool of the character described comprising an arm, a disk, means loosely connecting the disk to the arm, and a bearing member carried by the arm and engageable with the disk at a point closely adjacent the working surface thereof, said means and said bearing member cooperating to prevent removal of the disk from the arm.
